UNITED STATES PATENT OFFICE.

WAYNE E. BUMPUS, OF CHARLESTON, WEST VIRGINIA.

PACKING SETTER.

Application filed December 26, 1923. Serial No. 682,765.

To all whom it may concern:

Be it known that I, WAYNE E. BUMPUS, a citizen of the United States, residing at Charleston, in the county of Kanawha and 5 State of West Virginia, have invented a new and useful Packing Setter, of which the following is a specification.

This invention relates to a tool for setting ring packing in stuffing boxes around piston rods, shafts, or wherever it is desired to 10 place packing of this kind.

One of the objects of the invention is to provide a simple and efficient tool that can be easily placed astride the rod or shaft 15 which can thus be utilized as a guide on which the tool can be reciprocated for the purpose of forcing the packing into the stuffing box.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed may be made within the scope of what is claimed without departing from the spirit of the invention.

In the accompanying drawings the preferred form of the invention has been shown.

In said drawings—

Figure 1 is a side elevation of the tool in position for use, a stuffing box and packing being shown in section.

Fig. 2 is a plan view of the tool.

Fig. 3 is an elevation of one end thereof.

Fig. 4 is an elevation of the other end thereof.

Referring to the figures by characters of reference 1 designates a substantially circular head preferably formed of opposed semi-circular sections as shown. Each of these sections is riveted or otherwise fastened to one terminal of an elongated loop 2 preferably formed of a metal rod, the intermediate or crown portion of the loop being off-

set laterally as shown at 3 so as to straddle a shaft or an upstanding rod to which the tool is applied.

In Fig. 1 a portion of the stuffing box has 50 been shown at B and ring packing therein has been indicated at P. The shaft or rod extending through the stuffing box has been illustrated at S. After the packing has been placed in the stuffing box, the opposed side 55 portions of the tool are sprung apart so that the members of the head 1 can be placed astride the shaft or rod S at diametrically opposed points. When thus positioned the crown portion 3 of the tool will straddle the 60 rod or shaft as shown in Fig. 1. With the tool thus applied it can be reciprocated upon the shaft or rod S so as to press against the packing and force it tightly into the stuffing box. After the tool has been used it can be 65 removed easily simply by springing the sides of the loop 2 apart sufficiently to allow the members 1 of the head to be withdrawn from the shaft or rod.

What is claimed is:—

1. A tool of the class described comprising a split ring constituting a head, and an elongated loop having its free ends connected to the respective sections of the head, the intermediate or crown portion of the loop 75 being offset to straddle an object engaged by the head.

2. A tool of the class described including a head made up of opposed semi-circular members, an element bent to loop form and 80 having its terminals fixedly connected to the respective members forming the head, the intermediate or crown portion of the loop being offset laterally.

In testimony that I claim the foregoing as 85 my own, I have hereto affixed my signature in the presence of two witnesses.

WAYNE E. BUMPUS.
